United States Patent Office.

HENRY G. DAYTON, OF MAYSVILLE, KENTUCKY.

Letters Patent No. 62,187, dated February 19, 1867.

IMPROVED REFRIGERATOR AND WATER COOLER.

The Schedule referred to in these Letters Patent and making part of the same.

TO ALL WHOM IT MAY CONCERN:

Be it known that I, HENRY G. DAYTON, of Maysville, in the county of Mason, and State of Kentucky, have invented a new and useful Improvement in Water Coolers and Refrigerators; and I do hereby declare the following to be a full, clear, and exact description of the nature, construction, and operation of the same, reference being had to the accompanying drawings, which are made a part of this specification, and in which—

Figure 1 is a vertical central section of a combined water-cooler and refrigerator illustrating my invention, the plane of section being indicated by the line *x x*, fig. 2.

Figure 2 is a horizontal section through the plane of line *y y*, fig. 1.

Figure 3 is a detached view of the device whereby water is let into and drawn off from the cooler simultaneously.

Similar letters of reference indicate corresponding parts in the several figures.

My invention consists, first, in providing the water cooler with a double spigot or cock, so that as often as the water is drawn off from the ice chamber an equal quantity may be supplied thereto from an adjacent reservoir, by which means the temperature of the water is regulated and economy in the consumption of ice is effected; second, in the arrangement of a shelf and pan within the cooler to adapt it for the purposes of a refrigerator, as hereinafter described.

In order that others skilled in the art to which my invention appertains may be enabled to fully understand and use the same, I will proceed to describe it in detail with reference to the annexed drawings.

A may represent a water cooler of any suitable form and material. *B* represents a pan resting upon the bottom of the internal chamber *C*, and employed to contain the ice for cooling the water which is drawn from the cooler from time to time through the faucet *D*. *E* is another pan, which is supported upon or directly above the ice pan *B*, and has its bottom depressed at the centre to induce the water to flow therefrom through one or more small perforations, *e*. *F* is a water reservoir or vessel supported against the side of cooler *A*, in an elevated position relatively to the pans *B* and *E*. *G* is a pipe leading from the reservoir *F* into the chamber *C*, and so arranged as to discharge the water from *F* into the pan *E*. *D'* is the cock or spigot of the faucet *D*, upon which rests the lower end of the rod *G²*, upon the upper end of which is formed the cock or spigot *G¹* of the pipe *G*. The rod *G²* is properly centred upon the cock *D'* by the pin or pivot *g*. *H* is a handle, the socket *h* of which embraces the square head of the cock *D'* and the corresponding head on the lower end of the rod *G²*. Hence, by turning the handle *H*, the cocks *D'* and *G¹* are opened simultaneously, and thus, when a glass full of water is drawn off from the ice chamber *B* through faucet *D*, an equal quantity of water is supplied to the ice chamber from reservoir *F* through pipe *G*. By reason of this provision the ice chamber *B* need contain but a small quantity of water at a time; and therefore this cooler effects a considerable reduction in the consumption of ice, as the dissolving influence of the water is proportionate to the extent to which the surface of the ice is subjected to its action. Another advantage is that by maintaining a uniform quantity of water in the ice chamber, the water does not become intensely cold, whereas in other coolers the coldness of the water increases on account of the continued reduction in quantity. The pan *E* performs two useful functions, to wit: first, it deposits the water from the reservoir *F* into the ice chamber at the centre of the latter, or else at a point sufficiently removed from the faucet to prevent the newly supplied water from flowing directly out through the said faucet; secondly, it causes the water to trickle or flow in a small stream or streams into the chamber *B* and upon the ice, so as not (as it would by sudden and voluminous entrance) to materially change the temperature of the water already cooled in the ice chamber. The handle *H*, with its socket *h*, is susceptible of vertical adjustment, as indicated in red lines in fig. 3, so that, when desirable, the rod *G²* may be turned independently of the cock *D'*, for the purpose of letting water into the ice chamber without opening or drawing off through the faucet *D*. The chamber *C* is sufficiently cool to adapt it for the purposes of a refrigerator, to form which I arrange within the same the wire or open shelf *I*, which, for instance, may support milk pans, and the upper removable pan *J*, which may contain meat, etc. The removable top *A'* and door *A* render the pan *J* and shelf *I* accessible for the removal and deposit of the produce.

Having thus described my invention, the following is what I claim as new, and desire to secure by Letters Patent:

1. I claim the combination, with a water cooler A and reservoir or supply chamber F, of the double cock D' G^t or its equivalent, substantially as and for the purpose specified.

2. I claim the perforated pan E, arranged and employed in combination with the pipes G and D, in the manner and for the purpose set forth.

To the above specification of my improved refrigerator and water cooler combined I have signed my hand this second day of November, 1866.

HENRY G. DAYTON.
